UNITED STATES PATENT OFFICE.

GEORGE A. PARMENTER, OF BOSTON, MASSACHUSETTS.

PIPE AND NUT WRENCH.

1,155,955.

Specification of Letters Patent.

Patented Oct. 5, 1915.

Application filed June 2, 1915. Serial No. 31,717.

To all whom it may concern:

Be it known that I, GEORGE A. PARMENTER, citizen of the United States, residing at Boston, Massachusetts, have invented certain new and useful Improvements in Pipe and Nut Wrenches, of which the following is a specification.

My invention is a pipe and nut wrench, and my aim is to provide a very simple construction of few parts, effective in use, and not liable to get out of order.

In the accompanying drawing, Figure 1 is a side elevation with parts of the interior construction shown in dotted lines; Fig. 2 is a back view, and Figs. 3, 4 and 5 show details of the casing.

The handle and main body of the wrench shown at A, may be of any usual form as to its main shape and handle portion, but the shank is provided at its extreme end with a serrated face *a*, and a slightly inclined overhanging wall *b*, and is also provided with notches *c*. A casing B fits over the shank and its front walls have a pin *d* connecting them, and this pin is adapted to engage the notches *c*. The outer jaw C is carried by the casing B, as shown in Fig. 1, and has a serrated edge *a'* overhanging the complementary end *a* of the shank. The jaw C is pivoted to the casing B at *e* and has a slightly tapering end extending into the casing between the rear thereof and the wall of the shank as shown at *f*, and the inner face of the jaw is provided with a series of notches *c'*. The casing B has its lower end *g* normally pressed outwardly by a spring *h*, which is fastened at its upper end *i*, to the shank while its lower end presses against the rear inner wall of the casing and thus has a tendency to keep the pin *d* engaged with one of the recesses *c*. The casing B has a depending finger piece *k* serrated or roughened, and when it is desired to change the relation of the gripping jaws the finger piece is pressed inwardly, which disengages the pin *d* from the notch *c* and permits the casing B to be adjusted up or down, and after this adjustment has taken

place the spring *h* throws the casing rearwardly and engages the pin *d* with the notch *c*, which may be in line therewith. To still further hold the parts in their adjusted position I form a projection *l* on the rear face of the shank A, and this fits, according to the adjustment of the parts, into one of a series of recesses *c'* in the jaw C, to which reference has been made. As the casing B is pushed inwardly at its lower end to disengage pin *d* from its notch the same action disengages the notches of the upper jaw from the projection *l*, and when the parts are returned under the pressure of the spring *h* to normal position both the pin *d* and projection *l* engage the notches in line therewith and thus hold the jaws very securely in gripping position.

My construction is exceedingly simple and Figs. 3, 4 and 5 show the casing detached, Fig. 3 being a back view of Fig. 4, which is a side view of the casing, while Fig. 5 is a front view.

What I claim is:—

1. A pipe and nut wrench comprising a shank and handle, a casing connected to the shank adjustably and slidably, an outer jaw pivotally connected to the casing and a locking connection between the outer jaw and the shank, said connection being adjustable, and a gripping surface carried by the shank, substantially as described.

2. In a pipe wrench a shank, a casing carried thereby, said shank having a notched edge and a pin carried by the casing adapted to engage said notches, an outer jaw pivoted to the casing and having a shank depending within the same, said shank having notches, and a projection on the shank of the handle portion engaging said notches and co-operating with the notches and pin of the shank and casing, substantially as described.

In testimony whereof, I affix my signature in presence of two witnesses.

GEORGE A. PARMENTER.

Witnesses:

FRANK P. CROCKFORD,
CHAS V. SANDBERG.
